UNITED STATES PATENT OFFICE.

PETER H. MELANDER, OF TACOMA, WASHINGTON.

SHEARS.

No. 906,255.

Specification of Letters Patent.

Patented Dec. 8, 1908.

Application filed July 28, 1908. Serial No. 445,746.

To all whom it may concern:

Be it known that I, PETER H. MELANDER, a citizen of the United States, residing at Tacoma, in the county of Pierce and State of Washington, have invented certain new and useful Improvements in Shears; and I do hereby declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to new and useful improvements in shears and comprises various details of construction, combinations and arrangements of parts which will be hereinafter fully described and then specifically 20 defined in the appended claims.

I illustrate my invention in the accompanying drawings, in which:—

Figure 1 is a side elevation of my improved shears. Fig. 2 is a view of the 25 reverse side. Fig. 3 is a cross sectional view on line 3—3 of Fig. 1. Fig. 4 is a section through the pivot, boss and anti-friction roller, and Fig. 5 is an enlarged detail view of the anti-friction roller.

30 Reference now being had to the details of the drawings by letter, A and B designate the two blades of the shears, the former of which has a threaded aperture for the reception of a screw D, and the plate B is provided with 35 an elongated slot E with a shoulder E' formed in the marginal edge of the opening adapted to receive a sliding boss F having an elongated flange F' which is adapted to rest upon said shoulder. Said boss receives the 40 screw D and the head of the screw is slightly countersunk in said boss, as shown clearly in Figs. 3 and 4 of the drawings. An anti-friction roller, designated by letter H, is mounted about said boss upon which it has 45 a bearing and is interposed between the mar-

ginal walls of the slot E. A link K is pivotally connected at one end to a screw O fastened to the blade A and its other end is fastened to a screw R carried by the blade B.

By the construction shown, it will be noted 50 that, when the blades are opened and closed, a shearing cut as well as a longitudinal draw cut of the edges is effected, the link K causing one of the blades to be moved longitudinally as they shear. During this movement, the 55 anti-friction roller will bear against the opposite walls of the elongated slot E and reduce the friction to a minimum.

It will be understood that, while I have shown my invention as applied to pivotal 60 cutting shears of a certain kind, the principle involved in giving a draw cut may be applied to any form of shearing apparatus and may be of any shape and design.

What I claim to be new is:—

Shears comprising two blades, a pivotal screw mounted in a threaded aperture in one of said blades, the other blade provided with an elongated slot having a shoulder in the marginal edge thereof, a boss F having an 70 elongated flange, the opposite edges of which are parallel and adapted to rest and slide upon said shoulder, the ends of said flange being convexed and adapted to contact with the concaved ends of the opening in the blade to 75 limit the movement of one of the blades in opposite directions, an anti-friction roller mounted upon said boss and its upper end flush with the shoulder in said opening and its lower end adapted to rest upon the inner 80 face of the pivot carrying blade, and a link pivotally connecting the handles of the two blades, as shown and described.

In testimony whereof I hereunto affix my signature in the presence of two witnesses. 85

PETER H. MELANDER.
